VENETIAN BLIND OPERATING MECHANISM

Fred J. Burns, Saginaw, Mich., assignor to The Columbia Mills, Inc., Syracuse, N. Y.

Application December 19, 1949, Serial No. 133,792

1 Claim. (Cl. 160—176)

1

This invention relates to Venetian blind operating mechanism and more particularly to means for mounting and operating the head member of the blind.

One of the prime objects of the invention is to design a Venetian blind provided with simple, practical, and inexpensive means for attaching the head member in position and for rotation of said head member to tilt the blind slats and/or raise and lower them as desired.

Another object is to provide readily operable means mounted on the supporting bracket whereby the lift cords are pressed firmly into engagement with the cord sheave, so that the operation of the head member will be both smooth and positive.

A further object is to design a machine from which the head member can be easily and quickly removed or attached, and which firmly holds the blind at any set position of adjustment.

A further object still is to design a combination cord sheave stop by means of which the blind slat assembly can be tilted, raised and lowered from a single cord.

To the accomplishment of the foregoing and related ends, said invention then consists of the means hereinafter more fully described, and particularly pointed out in the claim, the annexed drawing and following description setting forth, in detail, certain means and one mode of carrying out the invention, such disclosed means and mode illustrating, however, but one of the various ways in which the principle of the invention may be used.

In the drawing:

Fig. 1 is an inside, face-elevational view of the operating mechanism of a Venetian blind with the head member omitted, and the stop bar in engaged position.

Fig. 2 is a transverse, fragmentary, sectional, front-elevational view taken on the line 2—2 of Fig. 1 and showing the head member in position.

Fig. 3 is a view similar to Fig. 1 with one of the sheave cheek plates removed and the stop bar in disengaged position.

Fig. 4 is an edge-elevational, detail showing the cord sheave.

The instant invention is directed to an operating mechanism wherein the raising and tilting is accomplished and controlled by a single cord or loop which hangs within easy reach of the person operating the blind.

Referring now more specifically to the drawing in which I have shown one embodiment of my invention, the blind-operating mechanism com-

prises a pair of brackets 6, only one of which is shown in the instant application, as all of the operating mechanism is mounted thereon. This bracket 6 can be of any desired shape, having an upper turned flange 7, and openings 8 are provided in said bracket to accommodate screws (not shown) for securing it in positon.

A centrally disposed pin 9 is mounted in the bracket 6, and a cord sheave S is journaled thereon, said sheave comprising spaced-apart cheek plates 11 and 12 having a plurality of thin disks 13 interposed therebetween, these disks and cheek plates being suitably bored to accommodate the pin 9, the outer periphery of the disks being formed with a plurality of relatively sharp spaced-apart teeth 14 over which the tilt cord C is trained.

Spaced-apart openings 15 are formed in the face of the cheek plate 12, said openings extending into said disks and accommodate a pair of gudgeon pins 16 which are mounted in the end of the head member or roller R on which the slat assembly (not shown) is mounted.

The outer periphery or rim of the cheek plate 11 is toothed as at 17, and a bar stop 18 is pivotally mounted on the bracket by means of a pin or rivet 19, this bar being curved as shown, and a projecting tooth 20 is formed on the inner edge of the bar for positive engagement with the toothed cheek plate 11 when it is desired to hold the head member roller in adjusted position.

The lower end of the stop bar is formed with laterally projecting ears 21 and the tilt cord C travels therebetween, said bar being swung about the pivot point 19 as the cord is pulled outwardly at an angle to disengage the tooth from the cheek plate 11 and the tooth is swung into engagement when the cord is swung inwardly towards the blind, all as shown in Figs. 1 and 3 of the drawing.

The cord sheave S is of limited diameter, consequently, it will be apparent that contact of the cord C with the periphery of the sheave S is also limited, and inasmuch as the cord is light and there is no added weight thereon, it is advantageous to press it firmly into engagement with the sheave, and I therefore punch a tab 22 in the side wall of the bracket 6 adjacent the upper flange 7 and bend it laterally into alignment with said flange, all as clearly shown in Fig. 2 of the drawing. I then provide a U-shaped spring 23 and mount it, legs down, between the tab 22 and the bracket flange 7, the horizontal section being bowed as at 24 so that it must be sprung into position, thus forcing the

legs 25 inwardly so that they resiliently press and bear against the tilt cord C, all as clearly shown in Figs. 1 and 3 of the drawing. This forces the cord tightly against the outer toothed periphery of the sheave S, so that the teeth 14 bite into the cord to eliminate slippage and provide for positive operation of the head member, and inasmuch as this cord serves to tilt as well as raise and lower the slat assembly, this is of extreme importance. The spacing of the gudgeon pins 16 provides ample leverage for rotation of the head roller R, and the entire assembly can be assembled on the bracket prior to its mounting.

From the foregoing description, it will be apparent that I have perfected a very simple, compact and substantial head member operating mechanism composed of relatively few parts for the purpose described, all of which can be readily manufactured and assembled.

What I claim is:

In a Venetian blind head roller mounting and operating sheave assembly adapted to be journaled on a pin on the inner face of a Venetian blind bracket, the combination comprising an outer cheek plate, stop engaging teeth on the outer periphery thereof, an inner cheek plate

spaced therefrom, a plurality of disks of lesser diameter than said cheek plates interposed between and tightly connecting said cheek plates, said disks being formed with sharply defined, raised edges on the outer periphery thereof over which the head roller tilt cord of a Venetian blind may be trained, said cheek plates and disks being provided with aligned, centrally disposed openings for accommodating said bracket pin, said inner cheek plate and said disks being provided with aligned spaced openings to accommodate the gudgeon pins of said roller.
